BAG SUPPORTING DEVICE

Allan C. Hoffman, Milldale, Conn., assignor to
 Scovill Manufacturing Company, Waterbury,
 Conn., a corporation of Connecticut

Application December 21, 1938, Serial No. 247,011

10 Claims. (Cl. 248—99)

My invention relates to foldable bag supporting devices or hangers for a new type of hot water syringe bag now appearing on the market and having a wide mouth or upper end portion which is attached to the device.

The purpose of the invention is to provide a simple yet durable support which when in use may be supported on a hook and when not in use can be folded up and packed away in a suitable compartment for future use.

A further object of the invention is to provide a simple and durable form of a collapsible frame comprising but three cooperating metal parts suitably joined together to permit the members to which the bag is attached to be moved with respect to the hanger member so that the bag may be readily folded while still supported in the frame, further to provide a bag supporting device which can be unfolded and attached to a hook on the wall in a way to allow the bag to be suspended and opened preparatory to filling with water.

With these and other objects in view the invention resides and consists in the construction of a frame formed of a few sheet metal and wire parts as illustrated, in the accompanying drawings, forming a part of this specification wherein similar characters of reference will be found to designate like or corresponding parts throughout the several figures, and of which,

Fig. 1 shows a perspective view of my improved bag supporting device having the upper portion of a bag attached and supported thereby in an open position.

Fig. 2 is a further perspective view of my improved device in a closed position, having a bag attached and also in a collapsed or closed position.

Fig. 3 shows a central vertical cross section through the device and bag illustrated in Fig. 1, the bag being broken away, better to illustrate the supporting loop of the wire member of the frame.

Fig. 4 is a perspective view of the device, the back being partially broken away and the wire frame member being extended and disconnected, showing the hanger irrespective of the bag.

Fig. 5 shows a perspective view of a modified form of the device having the upper portion of a bag in an open position, secured thereto and the lower portion broken away, the device being formed principally of wire and operates similar to the form shown in the preceding figures.

Fig. 6 shows the wire form of the invention with bag attached, both folded, forming an il-

lustration comparable with that of Fig. 2, and Fig. 7 shows a perspective view of a portion of the bag supporting device, somewhat like the illustration of Fig. 4.

Referring in detail to the characters of reference marked upon the drawings, 10 represents a back of the bag supporting device having an opening 11 in its upper end portion to permit it to be hung on a supporting hook, not shown. 12 represents a rectangular shaped wire frame, 10 the rear cross member of which is hingedly connected to the lower end of the back. The aligned forward end portions or stubs 13—13 of the wire frame are disposed inward in spaced relation to receive an attachable piece of light metal tubing 14. The forward top edge portion 15 of the rubber bag 16 in this instance is vulcanized to this tubing while the rear top edge portion 17 of the bag is similarly attached to the flattened piece of tubing 18 slidably mounted 15 on the back 10 beforementioned. In operating position the hinged wire frame member 12 is supported in a horizontal position, see Figs. 1, 3 and 4, by reason of an offset or loop 19 formed in its rear cross member 20 between the two 25 knuckles 21 of the supporting hinge and engaging against the back of the lower portion of the sheet metal back 10, see Fig. 3.

The opposite end portions of the rear cross hinge member 20 of the rectangular wire frame 30 12 are offset upwardly as at 22, see Fig. 4, which serve to dispose the main supporting part of the frame 12 and tubing 14 on a plane common with the upper end of the flattened piece of tubing 18 and thus supporting the open end 35 of the water bag 16 in substantially a horizontal position, see Fig. 2. It is obviously unnecessary to offset the wire frame 12 in the modified wire form of the invention because the rear wire supporting bar 18 and the tubing 14 are substantially on the same plane when the frame is in 40 an open position.

To close the bag, as shown in Fig. 2, and collapse the unit, the flattened piece of tubing 18, together with its attached rear edge portion of 45 the bag, is slid upwardly on the back which causes the wire frame to swing on its hinge and fold against the back and collapse the water bag in the manner illustrated in Fig. 2. From this position it is a simple matter to fold the 50 bag crosswise back upon the frame and itself so as to form a relatively small package that can readily be placed away.

What has been said of the general construction of the form shown in Figs. 1 to 4 inclusive 55

is applicable to a degree of the wire form shown in Figs. 5, 6 and 7. Here again the frame is formed of the same number of parts as that shown on sheet 1, the back member 10a in this instance is made of an inverted U-shaped piece of wire and to its lower ends is hingedly supported, the frame 12 carrying the tubular member 14 across its front end portion and to which the upper front edge portion 15 of the bag is vulcanized. This rectangular wire frame, like that shown in the previous figures, includes an offset loop 19 formed in the rear cross member 20 between the supporting knuckles 21 of the back to engage the cross bar 18 slidably mounted 15 on the back frame 10a and whereby the bag supporting frame is retained in a forwardly distended horizontal position. It will further be apparent that when the bag is empty the operation of this frame would be substantially the same as that before described to the effect that when the cross bar 18 is manually slid upward 20 on the back frame, causing the wire frame to pivot and fold against the back and collapse the hot water bag, the bag together with its supporting frame is drawn up into the folded position shown in Fig. 6.

Having thus described my invention, what I claim and desire to secure by Letters Patent is:

1. A water bag supporting device comprising a back, a rectangular wire frame hingedly connected to the back, a movable bar slidably on said back, a bag supported from the frame and the movable bar, means intermediate the rear cross member of said rectangular frame adapted to engage said back and support the frame in an extended horizontal position, said bar adapted to be slipped upwardly toward the top portion of said back causing the frame to pivot about its hinge and collapse the bag against the front face of said back.

2. A water bag supporting device comprising a back, a bar movably mounted on the back, a rectangular frame upon which a roller is mounted, a water bag secured to the bar and roller, said frame being hingedly connected to the back so as to allow its forward roller to be raised against the back, and means to support said frame in an extended horizontal position.

3. A bag supporting device for a water bag comprising a back, a bar slidably mounted thereon for vertical movement, a rectangular frame hingedly supported to the base of the back, means for supporting the frame in a horizontally extended position, said frame adapted to swing upon its hinge by the raising of the front member of the extended portion in a manner to cause an attached bag to be folded against the back.

4. A water bag supporting device comprising a back, a bar movably mounted on the back, a rectangular frame including a front cross member, a water bag secured to the bar and cross member, said frame being hingedly connected to the back so as to allow its front cross member to be raised together with a bag attached to the supporting frame and the bar, and means to support the frame in an extended horizontal position.

5. A water bag supporting device comprising a back, a bar slidably mounted thereon for vertical movement, a rectangular frame hingedly supported to the base of the back and including means for supporting the wire frame in a horizontally

extended position, a bag supported from said bar and the front cross member of said frame, said bag adapted to be collapsed by sliding the bar upwardly on said back and cause said frame to pivot on its hinge and swing against said back. 5

6. A water bag supporting device comprising a back, a bar slidably mounted thereon, a rectangular frame hingedly connected to the back and including a front and rear hinged member and having a loop formed in the rear hinged member of the frame that extends at a right angle to the side members of the frame, said loop serving to engage the back and support the wire frame in a horizontally extended position, so that a bag may be hung therefrom when secured to the slidable 15 bar and the front member of the frame.

7. A water bag supporting device comprising a back, a bar slidably mounted thereon, a wire frame member hingedly connected to the back, means for supporting the frame at substantially a right angle to the back, the front cross bar of the frame being rotatably mounted with respect to the other members of the frame, a water bag the rear top edge portion of which is secured to the slidable bar on the back and the front edge portion of the bag being connected to the front cross bar of the frame, the back and the frame being cooperatively connected so that with the raising of the bar on the back the bag and the frame will be raised, the latter from a horizontal 30 to a vertical position.

8. A water bag supporting device comprising a flat metal back having hinge barrels integral with its lower edge, a flattened tubular bar slidably engaged upon said back, a wire frame having one section hinged to said barrels with an intermediate loop to engage said back for holding the frame in a horizontal bag open position, the forward portion of said frame having inturned stub ends, and a round tubular bar rotatably mounted 40 on said stub ends, the side members of said frame being offset upwardly from the hinging section whereby said round tubular bar will be disposed on substantially the same plane as the upper edge of said flattened tubular bar when 45 the device is in a bag open position.

9. A water bag supporting device comprising a U-shaped wire back terminating at its lower ends in eye loops, a rectangular frame hingedly mounted on said eye loops having its intermediate 50 hinging end formed with an integral upstanding loop and its forward ends terminating in in-turned stub ends, a tubular bar rotatably mounted on said stub ends, and a wire cross bar looped around the wire rods of said back for slidably 55 engagement therewith, said bar when in its lowest position adapted to be engaged by said frame loop to hold said frame in a horizontal position.

10. A bag supporting device comprising a sheet 60 metal back, a bar slidably mounted on said back and removable therefrom, a wire frame comprising a rear member and opposite side arms, said rear member being hingedly connected to the lower end of said back, said arms being offset 65 relative to said rear member and provided at their free ends with inturned stub trunnions aligned with each other, a front cross member rotatably and detachably mounted on said stub trunnions, and a bag member attached to said bar 70 and said front cross member.

ALLAN C. HOFFMAN.
